GESELLSCHAFT, OF GLARUS, SWITZERLAND

PROCESS AND APPARATUS FOR PHOTOGRAPHIC TYPE-COMPOSING

Application filed June 25, 1930, Serial No. 463,761, and in Germany May 5, 1930.

For photographic type composing, as is known, a few simple printing character patterns are sufficient, which can be very easily and cheaply made, kept in stock, and easily changed, and admit of being reproduced photographically in any desired sizes. With this is also associated the fact that the finished form has practically no weight and occupies practically no space in comparison with a lead type form, and can be quickly and easily manipulated quite accurately by purely mechanical means, and can be readily enlarged photographically. As a set off against these main advantages there are certain difficulties which are experienced in ensuring the letter press space breadths of the different forms of letters, and in the justification of the lines, and also in the supervision and correction of the form. These three main disadvantages follow from the circumstance that the spatial displacement capacity and the tangibility of the forms of letters embodied in lead are completely absent from the projection images to be composed. The suggestions hitherto made relating to photographic type composing tend to replace the advantageous properties of the printing type characters in the case of projected images by indirect means, in that they involve a complicated and expensive new plant, comprising numerous unreliable component parts, and in conjunction therewith a complete re-training of the compositors. Now the object of the present invention is to unite the main advantages of photographic type composing with the main advantages of separate setting, without the disadvantages indicated. The process according to the invention consists essentially in the fact that the printing characters during the preparation of the active mechanical control impulses under the supervision of the compositor himself, are represented by those control bodies, which, in conjunction with one or more particular controlling values which accurately determine the printing character in question mechanically, and which the said printing bodies already embody in themselves, or carry with them in

the form of control impulse selections, admit of being handled as freely as printing type characters or the like. The requisite corporeal properties of the printing characters are accordingly to be represented as detached from the projected image itself, and the mechanical and optical parts embodied, which are separated from one another to the greatest possible extent, are each to be handled under their most favourable operative conditions. The mechanical cohesion of the two parts will admit of being reduced to a minimum in the form of a mere feel of control or the like. 55

The control bodies are according to the invention first set up into control lines in the manner of printing characters, this being done simply as if they were printing type or the like, and are also justified, and the line to be printed is then mechanically controlled 60 step by step along the control line. 65

The employment of such control bodies, and also the previous assembling and the arranging thereof into control lines of predetermined length, need not in reality involve any appreciable sacrifice, because control bodies already arranged in stacks, for the controlling of control lines in the manner of the matrices of ordinary type-setting machines, may be assembled and distributed 70 in a mechanical circuit, and therefore with the readiness to which the compositor is accustomed. Photographic type composing will accordingly proceed of itself with the skill of the composing machine work. Furthermore the time needed for the separate phase required for the formation of a control line will admit of being saved, owing to the fact that the preceding controlled line is set up and justified during the controlling of 75 the next following line. 80

The processes described yield tangible carriers of the controlling values occurring, which are intended to present the space breadths of the letters or the like embodied 85 thereby with the clearness and intelligibility of printing type or the like, and in themselves alone to represent the decisive qualities of the printing characters, without participating themselves directly in the print- 90 100

ing, or being themselves bound directly to the printing character image in the giving of dimensions or in the performance of their other duties. The space breadths and the 5 justifying will therefore be effected as in the case of type printing or the like. In the course of this specification it will be shown that the problem of supervising and correcting has also been solved and furthermore 10 that the controlling values of the controlling bodies can be transmitted with change of amplitude.

A few constructional forms of control 15 bodies and photographic type-composing machines according to the invention are diagrammatically illustrated in the accompanying drawings, in which

Figures 1, 2 and 3 are perspective views of 20 three different control bodies,

Figure 4 shows a longitudinal section of a 25 control line in a collector, where the control bodies appear in a horizontal central section through Figures 1 to 3,

Figure 5 is a broken longitudinal section 30 of a control line, together with further controlling devices, where the control bodies appear in vertical longitudinal section through Figures 1 to 3,

Figure 6 is a cross section of similar 35 members in another constructional form, a control body according to Figure 2 being shown in elevation, and

Figure 7 shows a general view of a photographic type-composing machine in perspective and partly in cross section.

In Figures 1, 2 and 3, three control bodies 1, 1¹, and 1² are shown, provided with pairs of lugs 2 and with distributing teeth 3 of the nature of the matrices of type-composing 40 machines, which fit directly into the usual composing machines. The control bodies show the block-like form of base of the matrices, with guiding surfaces extending in the direction of the lines, and with 45 lateral bounding planes perpendicular to the guiding surfaces, but as contrasted with the matrices they embody a plurality of controlling values in the form of impulse delivering lengths of different linear dimensions. They should accordingly be accurately machined, and can be fitted to the 50 variables occurring, according to the simplest conditions.

The control dimensions X¹, X² and X³ of the breadths of the particular printing characters are represented by the distances of the two lateral boundary planes from one another; but the control dimensions Y¹, Y² and Y³ of the printing character selection 55 are provided in the form of slots, 4¹, and 4², which extend through the control bodies in the direction of the line, the decisive longitudinal dimensions thereof being perpendicular to the direction of the line. The

different controlling values accordingly admit of being embodied independently of one another.

The control bodies, like the matrices, are arranged in a line L like a line of printing 70 in a collector 5 (Fig. 4), and this line serves to control those photographic functions which are required for the preparation of the actual photographic form to be produced. The collector 5 is longitudinally 75 slidable in a guide 6, for the purpose of enabling the finished control line L to move past in front of an actuating position not extending beyond the reach of a control body, during the controlling operation. It 80 tends to pass into its end position, towards which it is pulled by a cable 10, secured at 85 7, passed round an independently supported roller 8 and loaded with a weight 9, but it is checked step by step according to the measure of stop surfaces on the control bodies, which are placed in the direction of the line, so that the controlling proceeds 90 from one printing character to the next in series.

Such a stop surface is obtained without impairing the outline illustrated in Figures 1 to 3 in the following manner:

On the control bodies 1, of the two wide 95 sides 11 and 12, in general only the former is left straight, while the latter is bevelled rearwardly in the direction of the line. In the sequence of control bodies 1 closed to form a line L there accordingly occurs a cam surface of saw-toothed section, where 100 the parts 13 remaining uncovered serve as stop surfaces.

All that now need be done is to provide suitable plungers in a stationary position in the region of the path of the collector and to actuate them periodically in any convenient manner, in order that the controlling values contained in the line L may be transmissible mechanically. Figure 4 shows for example a bolt-shaped plunger 16, sliding to and fro in a guide 14, and acted upon by a spring 15. If this plunger is somewhat lifted in the direction of the arrow at one moment and then released, that is to say, merely lifted over the upper edge of the stop surface 13, the collector 5 slides as a whole towards the left, until the plunger 16, feeling the wide side 12, strikes against the next following stop surface 13. The longitudinal displacement of the collector 5 thus obtained 110 accurately returns the controlling dimension falling into the line direction, of the control body 1 in question, and this dimension in its turn is proportional to the breadth of the particular printing character. The collector 115 displacement in question can accordingly be employed mechanically, either directly or with the interposition of any desired transmission ratio, for the adjustment of that light-sensitive support which has to re- 120 125 130

ceive the actual photographic form. This will be further explained with reference to an example in conjunction with the description of Figure 7.

5 It is also to be observed that the wide side 12 of the control bodies 1² or 1³, which represent stationary or justifiable filling pieces, are not bevelled but straight. The full wide sides slide past underneath the plunger 16 without being checked, and hand in hand therewith the light-sensitive support is smoothly and idly fed forward correspondingly to such positions.

It is also necessary to take care that in 15 the photographic type-composing device itself the pattern of that particular printing character which is represented by the particular control body is always adjusted for photographing. For this purpose the selector slots 4 co-operate according to Figure 5 with a feeler-like plunger 17. The latter is periodically actuated by the aid of a compressed air cylinder 18 and its piston 19, with which it is connected by means of a 20 rack 20. The latter meshes with a pinion 21, and a toothed wheel 22 keyed to the pinion 21 meshes with a rack 23, which in its 25 turn is connected with a glass plate 24.

The glass plate 24 is the carrier of various transparent printing character patterns, which are arranged in a line thereon, and which pass individually into the stationary photographing position of a photographic composing device according to the 30 amplitude of the longitudinal displacement of the glass plate 24. It therefore depends ultimately upon the height Y of the selector slots 4 that limit the plunger strokes, how far the glass plate 24 is displaced, that 35 is to say, which printing character pattern thereon is adjusted. It is therefore only necessary to dimension the slot heights Y proportionally to the longitudinal co-ordinates of the positions occupied by the printing character patterns on the glass plate, in order that to each printing character pattern there may correspond a selector slot of 40 its own on its control body.

If for example there are forty-six different printing characters, and therefore forty-six patterns provided on the glass plate 24, forty-six control bodies will have to be provided with an equal number of different slot heights. If, however, the patterns on the 45 glass plate are arranged in two or more rows it will suffice to provide one and the same selector slot height for all the patterns that have the same longitudinal co-ordinate on the glass plate 24. Figure 6 shows a 50 changing device suitable for this purpose for a glass plate having two rows. The control body 1¹, in addition to the selector slot 4¹, which, like the selector slot 4, co-operates with a plunger device according to Figure 5, 55 has an auxiliary selector slot 4², which in

its turn co-operates with a second plunger device. The latter is similar to the one described in connection with Figure 5, except that the toothed wheel 22¹ now actuates a connecting rod 27, provided with a toothed segment 25 and supported at 26. The selector slots 4² are equal to one another in all the control bodies that come into consideration for the second row of patterns on the glass plate, and are accurately dimensioned in such a way that they ultimately bring about a raising or lowering of the glass plate 24 in a direction transverse to the rows of patterns.

70 In control bodies according to Figure 1, which are not provided with a second slot, the plunger 17² cannot penetrate so far that it will bring about an exchange. Such control bodies will be employed for example for the small letters, while the control bodies for capital letters will be provided with auxiliary slots. Accordingly one row on the glass plate 24 will contain the small letters and the other row the capital letters. In 75 control bodies of stationary or justifiable filling pieces no selector slots at all are necessary, because the same have nothing to be adjusted for photographing.

80 Figures 1, 2 and 4 show that on the wide sides 11 indicating marks 28, 28¹ and so forth may be provided, which immediately indicate the printing character that is represented by the control body in question. These indicating marks preferably project 85 so far that they enable a proof impression to be taken from them, which enables the work to be supervised and discloses at the outset any errors occurring. If the control line is released by lifting the line-limiting jaw 31, which is adjustable by means of a hand crank 29 and a spindle 30, everything 90 can be corrected before the photographic form is produced.

95 In Figure 7 will be seen the main parts of a photographic type-composing machine, where the plunger strokes, influenced by the selector slots 4, are transmitted to a photographic composing device with a drum-shaped pattern carrier. The rack 20² carrying the plunger 17³ rests in the inoperative 100 position on a stop 35, and the up strokes permitted by the various selector slots 4 set the pinion 21² in rotary motion, which is transmitted by means of a shaft 36 and of 105 two bevel wheels 37, 38 to a vertical shaft 39. The latter carries at its upper end an inclined mirror 40 which reflects rays of light coming from a lamp 41 along a path indicated by dot-and-dash lines, by way of two 110 inclined annular mirrors 42 and 42¹, to an inclined mirror located at the inner end of the shaft 39, and from here into a photographic objective lens 43. A stationary disc 44 carries a glass drum 45, on the periphery of which the transparent printing 115

character patterns are arranged in belts 46, 46¹ and 46². With the shaft 39 there also revolves in the direction of the arrow the upper half 47 of a ratchet mechanism provided with wedge teeth, while the lower half 47¹ of the ratchet mechanism is stationary, and can be raised and lowered by means of rods 48.

The up strokes of the plunger 17³ ultimately each rotate the shaft 39 through a definite angle. The different angular rotations of the latter involve different photographic adjustments, because the two inclined mirrors mentioned above are rotated with it, and the rays of light from the lamp 41 pass round the circuit of the belts 46², and therefore illuminate just that particular printing character pattern which corresponds to the particular selector slot 4.

Now to the longitudinal co-ordinates of the glass plate 24 of Figure 5 there correspond the partial rotations of the shaft 39, and the auxiliary slots have here to provide for the raising of the particular belt of printing characters 46, 46¹ or 46² to the level of the lower annular mirror 42¹. The displacements effected by the selector slots 4 are adjusted by the fact that the lower half 47¹ of the ratchet mechanism is raised at suitable moments. The wedge effect of the teeth is thus intended to ensure the accuracy of the adjustments. The flexibility of the driving mechanism requisite for this purpose may be obtained by interposing an elastic element at any convenient position. Such an adjustment is of course also possible in other pattern carriers.

The light-sensitive support is displaced by the aid of a two-armed lever 49, the pivot 50 of which, for the purpose of regulating the transmission ratio, is shifted on a slide 52 in a guide 51 and can be made fast by means of a screw 53. The lever 49 is attached to the collector 5¹ at one end in longitudinal slots 54, 54¹ and at the other end by a pin 55 to a slide 56, which takes with it stepwise by means of a pin 59 a strip of film 58 unwinding in the direction of the arrow from a roll 57, as it is liberated by the plunger 16¹ in proportion to the corresponding stops of the control bodies. The slide 56 is constantly pulled in the direction of the arrow towards its end position by a cable 10¹ passing over a pulley 8¹ and loaded with a weight 9¹. From one control body to the next, that is to say, from one printing character to the next, the shaft 36 is rotated at will, and therefore the corresponding character pattern is illuminated on the glass drum 45 and projected through the objective lens 43 to the constant exposure point 60, while the strip of film 58 is fed forward according to the particular breadth dimensions of the control bodies, so that the exposure always takes place on fresh film sur-

faces. Since the lines, while still in the condition of control lines, are already justified and supervised, the photographic exposures may be effected in rapid succession. For this purpose alone the succession of the ⁷⁰ plunger actuations is to be effected with corresponding rapidity, because during the controlling the collector, and also the film slide, have a constant tendency to shift in the direction of their length, and it is accordingly merely a question of an escape-⁷⁵ment-like checking of these constant displacement tendencies.

Figure 7 shows merely a one-line photographic form. Multi-line photographic ⁸⁰ forms in column form can likewise be made, only a corresponding line displacement of the light-sensitive support has to be provided for. The drawing in fact indicates the ⁸⁵ existence of the photographic form on the film strip 58, but the same in reality only becomes visible after photographic development, and so forth.

The plunger 16, in the position of the collector 5 adjusted for the commencement of ⁹⁰ the controlling of a line, has to check the latter at the initial stop surface 13 of the initial control body. This precaution is intended to determine in the first place the most advantageous arrangement of the ⁹⁵ plunger 16 and to ensure in the second place that the photographic exposures can precede the adjustments from time to time of the light-sensitive supports.

On similar grounds the plungers 17 co-¹⁰⁰operating with the selector slots 4 have to be located, in the position of the collector 5 just mentioned, within reach of the narrowest initial control body occurring. In the case of the other control bodies under consider-¹⁰⁵ation the selector slots 4 prove longer in the direction of the line, so that the up-strokes of the plungers 17 can always terminate smoothly. The pneumatic operation of the latter exerts moreover a buffer-like ¹¹⁰action, so that the plunger strokes can be directly lengthened or shortened. Figures 4, 5 and 6 indicate that the two kinds of control devices can be connected with one another. To the plunger 16 of Figure 4 is pivoted the key 32 of a cock 33, which opens and closes the compressed air supply pipe 34. The latter is continuous with pipes 34¹, 34² and 34³, which open in the corresponding cylinders 18, 18¹ and 18². These accordingly receive their supplies of compressed air under the control of the strokes of the plunger 16.

The photographic composing machine de-¹²⁵scribed may as a whole consist of an ordinary type-setting machine, in which the control bodies 1 described above are employed in place of the matrices, the longitudinally slidable collector 5, together with the plung-¹³⁰

ers 16 and 17 hereinbefore described are used instead of the ordinary collector, and a photographic type-composing device is employed in place of the casting and line-treating device, this composing device being controlled by means of the control bodies. Accordingly a comparatively small number of control bodies will be sufficient and will facilitate the introduction of the photographic composing machines, both from the point of view of the owner and from that of the operators.

Finally it may be mentioned that the invention is intended to eliminate devices that are unreliable in operation. As an example of this there may serve the fact that according to the above description no electro-magnet has to be employed.

What I claim is:—

1. A photographic type-composing process, comprising setting up by a succession of manual operations separate movable control bodies each representing a printing character, and deflecting a beam of light into a direction determined by certain dimensions of each of the said control bodies in succession, thereby causing the corresponding printing characters to be photographed on a moving sensitized strip.

2. A photographic type-composing process, comprising forming a control line by setting up by a succession of manual operations movable control bodies each representing a printing character, justifying the control line, and deflecting a beam of light into a direction determined by certain dimensions of each of the said control bodies in succession, thereby causing the corresponding printing characters to be photographed on a moving sensitized strip.

3. A photographic type-composing process, comprising forming a control line by setting up by a succession of manual operations movable control bodies each representing a printing character, justifying the control line, deflecting a beam of light into a direction determined by certain dimensions of each of the said control bodies in succession, thereby causing the corresponding printing characters to be photographed on a moving sensitized strip, and forming a further control line of movable control bodies while the control line previously set up is controlling the photographing of the printing characters represented thereby.

4. A photographic type-composing process, comprising forming a control line by setting up by a succession of manual operations movable control bodies each representing a printing character, justifying the control line, and deflecting a beam of light into a direction determined by certain dimensions of each of the said control bodies in succession, thereby causing the corresponding printing characters to be photographed on a

moving sensitized strip, the control bodies being assembled from stacks and re-distributed thereto after use in a mechanical circuit like the matrices of a type-setting machine.

5. A photographic type-composing machine, comprising a longitudinally slideable collector adapted to assemble control bodies representing particular printing characters into control lines.

6. A photographic type-composing machine for carrying out the process claimed in claim 1, comprising a longitudinally slideable collector adapted to assemble control bodies representing particular printing characters into control lines.

7. A photographic type-composing machine, comprising a longitudinally slideable collector adapted to assemble control bodies representing particular printing characters into control lines, a plunger mounted near the path of the collector and adapted to co-operate step by step with the control bodies assembled therein, and means for periodically reciprocating the plunger.

8. A photographic type-composing machine, comprising a longitudinally slideable collector adapted to assemble control bodies representing particular characters into control lines, plungers mounted near the path of the collector and adapted to co-operate step by step with the control bodies assembled therein, and means for periodically reciprocating the plunger.

9. A photographic type-composing machine, comprising a longitudinally slideable collector adapted to assemble control bodies representing particular printing characters into control lines, a plunger mounted near the path of the collector and adapted to co-operate step by step with the control bodies assembled therein, and means for periodically reciprocating the plunger, the plunger engaging with the outer end face of the initial control body when the collector is in its starting control position.

10. A photographic type-composing machine, comprising a longitudinally slideable collector adapted to assemble control bodies representing particular printing characters into control lines, a plunger mounted near the path of the collector and adapted to co-operate step by step with the control bodies assembled therein, and means for periodically reciprocating the plunger, the line of action of the plunger being in such a position in relation to the path of the collector that it can engage adequately with even the narrowest of the control bodies when occupying the initial position in the control line.

11. A photographic type-composing machine resembling in general arrangement an ordinary type-setting machine, but comprising a longitudinally slideable collector adapted to assemble control bodies representing particular printing characters into control

- lines, a plunger mounted near the path of the collector and adapted to co-operate step by step with the control bodies assembled therein, and means for periodically reciprocating the plunger in place of the usual matrices and matrice-collector, and photographic type-composing means controlled by the said control bodies in place of the usual casting and line-treating means.
- 10 12. A photographic type-composing machine, comprising a longitudinally slidable collector adapted to assemble into control lines, control bodies representing particular printing characters and having certain linear dimensions that differ from the corresponding linear dimensions of similar control bodies representing other printing characters, and comprising guiding surfaces substantially parallel to the direction of the line of control bodies when set up, and lateral bounding planes perpendicular to the said guiding surfaces.
- 15 20

In testimony whereof I have signed my name to this specification.
